9 Claims. (Cl. 197—82)

1

In general the types of typewriters for typing from right to left, of which the manufacture is much less extensive usually than that of machines for typing from left to right, differ from the latter by some modifications for adapting them to the particularities of the language (for example Hebrew, Arabic and so forth). Manufacturers are compelled to reduce to a minimum the necessary modifications for reasons of standardization and cost. The mechanisms chiefly affected by the adaptation, in a normal typewriter (typing from left to right), for reversed typing, are the control of the line spacing lever from the right to left, the back space key, the return for the carriage, the tabulator and so forth; but the mechanism which requires the most considerable conversion is formed by the assembly of the members ensuring the escapement of the carriage in the opposite direction, from right to left. These members, in nearly all modern typewriters, include, amongst other things, the escapement device proper, with its normal controls and back space key, the toothed pinion and the rack.

The reversal of the direction of actuation of these members is generally obtained by means substantially affecting the construction and necessitating the addition of supplementary parts or the replacement of normal parts by separate parts. These known means are more particularly the reversal of the escapement with conversion of the securing and of the connections which lead to this device (normal control and back space key); the addition of an intermediate pinion between the main pinion of the escapement and the rack of the carriage; and the replacement of the normal escapement by a separate reversed escapement, particularly conceived and manufactured for this purpose.

The present invention has for its subject a typewriter provided with a framework carrying a carriage of which the movements are controlled by a pinion gearing with a rack and provided with a device for reversing the direction of advance of the said carriage. This typewriter is distinguished from known typewriters by the fact that it is provided with a device for securing the rack enabling it to be placed into two symmetrical positions relatively to the said pinion and thus modifying the direction of feed of the carriage.

The accompanying drawing shows diagram-

2

matically and by way of example typewriters provided with two different forms of construction of the device.

Fig. 1 is a side view, with parts broken away, of a typewriter provided with a device according to a first form of construction.

Fig. 2 is a detail view, to a larger scale, of a modification of the device shown in Fig. 1.

Fig. 3 is a side view, with parts broken away, of a typewriter provided with a device according to a second form of construction.

Fig. 4 is a detail view, to a larger scale, of the device shown in Fig. 3.

The machine shown in the drawing is provided with a framework 1 on which slides a carriage 2 carrying the platen 3. The movements of the carriage are guided by rails 4 provided on the said carriage, on the one hand, and on a support 5 secured to the framework, on the other hand, and between which are located balls 6 or other rolling members. Like all other typewriters, that shown is provided with an escapement device 7 controlling the step by step feed of the carriage during typing. The escapement device, secured rigidly to the framework 1, is provided with a pinion 9 gearing with a rack 10 carried by the carriage 2.

A typewriter according to the invention is provided with a securing device enabling the said rack to be placed on the carriage in two symmetrical positions relatively to the pinion 9 and which consequently enables the desired direction of feed of the carriage to be obtained by selection of the securing position of the rack on the carriage.

In the form of construction shown in Fig. 1, the rack is carried by supports 11 (of which one only is shown in the drawing), of general U-shape. The rack is secured to the end of one of the limbs of the U, whilst the other limb is secured to the carriage 2 by a securing member 12. The securing member is located in a horizontal plane passing through the axis of the pinion 9 so that the supports 11 may be secured to the carriage, either in the position shown in full lines, in which the rack gears with the upper teeth of the pinion, or in the position shown in chain dotted lines, in which the rack gears with the lower teeth of the pinion 9. From the foregoing and by examination of Fig. 1, it will be seen

clearly that according to the position of securing the supports 11, the rack is located in one or the other of two symmetrical positions relatively to the pinion 9 and that consequently by simply selecting the position of securing the rack to the carriage, the manufacturer has the possibility of obtaining the control of the carriage in one direction or the other by the pinion 9, without modifying any part or element of the escapement.

In the modification shown in Fig. 2, is shown a part of the framework 1 of the machine, on the one hand, and a part of the carriage 2 on the other hand. The first carries the escapement wheel 7 and the pinion 9. To the second, which is opposite thereto, are secured, by screws 12a located in the plane of the axis of the pinion 9, the supports 11 of the rack.

As explained with reference to Fig. 1, the supports may occupy the position shown in full lines or in chain dotted lines according to the desired direction of feed of the carriage.

In the form of construction shown in Figs. 3 and 4, the typewriter is provided with a clutch lever 13, pivoted at 14 on a part of the carriage and subjected to the action of a spring 16 tending to hold it in contact with a stop 17. The lever is connected to one of the supports 11 by a link 15 hinged at one end, at 25, to the lever 13 and at the other end, at 26, to the said support 11. The supports 11 are not secured rigidly to the carriage but can oscillate on their securing members 12b, so that when actuating the lever 13, the user produces oscillation of the supports 11 and the disengagement of the teeth of the rack 10 from those of the pinion 9. Thus, the mechanical connection between the escapement and the carriage is interrupted so that the latter may be actuated freely in order to move it rapidly into a desired position.

When the manufacturer of the machine desires movement of the carriage in the opposite direction, he secures the rack to supports 18 oscillating on securing members 19 carried by the carriage. The supports 18 are identical with the supports 11 and support with these a common trunnion 20 which engages with a semi-circular notch provided in the end of each of the supports 11 and 18. As the action of the toggle is the same, whether the lever 13 is moved towards the left or towards the right, it is possible at will to replace the stop 17 and the spring 16 by a stop 21 and a spring 22. As described above, a push applied to the lever 13, against the action of its return spring, produces the disengagement of the teeth of the rack from those of the pinion 9. In fact the supports 18 are caused to carry out an angular movement by the trunnions with which they engage, at the same time as the supports 11.

The stops 17, 21 respectively, as also the hinge axis of the clutch lever on the carriage, are so arranged that when the rack is in the engaging position with the pinion 9 and the lever 13 is held in contact with its stop by its return spring, the three hinge points 17, 25 and 26 are located on a straight line. In this manner there is obtained a toggle which, in the position of service of the rack (shown in the drawing), opposes the tendency of the pinion and the rack from moving apart under the action of the radial component of the force which is applied to the teeth.

I claim:

1. A typewriter comprising a framework, a carriage movably mounted in said framework, a

platens mounted on said carriage, a rack on said carriage, a pinion rotatably mounted in said framework and engaging with said rack, and means reversibly securing said rack to said carriage, said securing means mounting said rack in either of two symmetrical positions relatively to said pinion so as to modify the direction of movement of said carriage.

2. A typewriter according to claim 1, wherein 10 said securing means for said rack comprises supports and for each support a member for reversibly securing same to said carriage, said member located in a plane parallel to the axis of the platen and containing the axis of rotation of the pinion with which said rack engages.

3. A typewriter according to claim 1, wherein 20 said securing means for said rack comprises supports and for each support a member for securing same to said carriage, said member located in a plane parallel to the axis of the platen and containing the axis of rotation of the pinion with which said rack engages, said supports being of general U-shape and carrying the rack at the end of one of their limbs, the other limb 25 serving to secure said supports.

4. A typewriter according to claim 1, wherein 30 said securing means for said rack comprises supports and for each support a member for securing same to said carriage, said member located in a plane parallel to the axis of the platen and containing the axis of rotation of the pinion with which said rack engages, said supports being secured laterally to said carriage.

5. A typewriter according to claim 1, wherein 35 said securing means for said rack comprises supports and for each support a member for securing same to said carriage, said member located in a plane parallel to the axis of the platen and containing the axis of rotation of the pinion with which said rack engages, the axes of the securing members of said supports being located parallel to the axis of rotation of said pinion.

6. A typewriter according to claim 1, wherein 45 said securing means for said rack comprises two identical, oppositely arranged supports and for each support a member for pivoting same to said carriage, said members being located symmetrically with regard to a plane parallel to the axis of the platen and containing the axis of rotation of the pinion with which said rack engages, and said typewriter also comprises an actuating lever, and a return spring associated with said actuating lever, said lever acting on the supports for the rack so as to move the rack into and out 50 of engagement with said pinion.

7. A typewriter according to claim 1, wherein 55 said securing means for said rack comprises two identical, oppositely arranged supports and for each support a member for pivoting same to said carriage, said members being located symmetrically with regard to a plane parallel to the axis of the platen and containing the axis of rotation of the pinion with which said rack engages, and said typewriter also comprises an actuating lever, a return spring associated with said actuating lever, said lever acting on the supports for the rack so as to move the rack into and out of engagement with said pinion, and a toggle between the lever and the supports, said lever acting on said supports through the medium of said toggle which, in the normal position, automatically locks the supports against release under the action of the force exerted on the teeth of the pinion and rack.

8. A typewriter according to claim 7, wherein

one of the supports is directly acted upon by the actuating lever through the toggle and mounts the rack in position for moving the carriage in one direction, the other support serving to mount the rack in position for moving the carriage in the opposite direction, and a connecting member common to said two supports is provided for moving the same in unison.

9. A typewriter according to claim 8, wherein said connecting member common to said two supports is formed by a trunnion which engages with recesses in the oppositely located ends of said supports.
